UNITED STATES PATENT OFFICE.

WILLIAM F. DUNLOP, OF NEW YORK, N. Y.

COMBINED MOUTH PROP AND ILLUMINATOR.

1,122,086.

Specification of Letters Patent. Patented Dec. 22, 1914.

Application filed September 22, 1914. Serial No. 863,003.

To all whom it may concern:

Be it known that I, WILLIAM F. DUNLOP, a citizen of the United States, residing at New York, in the county of New York and 5 State of New York, have invented new and useful Improvements in Combined Mouth Props and Illuminators, of which the following is a specification.

This invention relates to combined mouth 10 props and illuminators and it consists in the novel features hereinafter described and claimed.

An object of the invention is to provide a 15 combination dental appliance of the character indicated which includes adjustable means for propping the jaws apart, also means for illuminating the mouth.

With the above objects in view the appliance comprises a body pivotally mounted 20 upon a saddle member the said saddle member being adapted to straddle the teeth of the patient. A rest is adjustably mounted upon the body member and is also adapted to engage the teeth of the patient. A miniature 25 electric lamp or bulb is mounted in the body and means is provided for supplying current to the said bulb. Also means is provided for turning the body with relation to the saddle and the rest.

30 In the accompanying drawings:—Figure 1 is a perspective view indicating the manner in which the device is applied to the mouth of a patient. Fig. 2 is a side elevation with parts in section of the device. 35 Fig. 3 is an elevation of the device showing the same at a right angle to the view as shown in Fig. 2.

The combined mouth prop and illuminator comprises a body 1 which is pivotally 40 mounted upon a saddle member 2 adapted to straddle the teeth of a patient. A member 2 is provided at the under side of the intermediate portion with a suitable cushion 3 of any material as for instance cork or the like. The cushion 3 is held in position in the member 2 by means of inwardly disposed 45 ribs 4 formed at the opposite side portions of the member.

An electric light bulb 5 is inserted in the 50 body 1 and a cap 6 is detachably and turnably mounted upon the body 1 and is provided with a tube 7 through which electric wires 8 are passed and which leads to the bulb 7 for the purpose of supplying electric 55 current to the same.

Copies of this patent may be obtained for five cents each, by addressing the "Commissioner of Patents, Washington, D. C."

A cup-shaped member 8 is provided with a threaded shank 9 which is screwed into the upper portion of the body 1. A cushion 10 is located in the cup-shaped member 8 and is adapted to bear against the teeth of the upper jaw of a patient when the device is applied as best indicated by Fig. 1 of the drawing. The first cup-shaped member together with the attached shank and the cushion contained therein constitute a rest 60 for the upper teeth of the patient. The body 1 is provided at its lower portion and at the opposite sides of a line passing vertically through its center with openings 11 into either one of which may be inserted the 65 end portions of an angular tube 12. A pipe 13 is detachably connected with the upper end portion of the tube 12 and a flexible tube 14 is connected with the pipe 13 and may be immersed in running water whereby 70 a suction may be created through the same causing the tube 12, pipe 13 and said tube 14 to serve as a drain for the saliva when the device is in position in the mouth.

From the above description taken in connection with the accompanying drawing, it will be observed that the cup member 8 is adjusted with relation to the body 1 whereby the jaws may be held apart at a desired distance and when the device is applied to 80 a patient the body 1 may be turned in order to direct the rays of light from the bulb 5 at any particular part of the mouth and also means is provided upon the body 1 for draining the saliva from the mouth of the 85 patient.

Having described the invention what is claimed is:—

1. A dental prop comprising a body member, teeth engaging members mounted thereon and an illuminator carried by the body member and located between the teeth engaging members.

2. A dental prop comprising teeth engaging members, a body turnably mounted 95 thereon and an illuminator carried by the body.

In testimony whereof I affix my signature in presence of two witnesses.

WILLIAM F. DUNLOP.
